UNITED STATES PATENT OFFICE.

WILLIAM H. CALLAN, OF CLEVELAND, OHIO, ASSIGNOR TO CHICAGO PNEUMATIC TOOL COMPANY, OF NEW YORK, N. Y., A CORPORATION OF NEW JERSEY.

APPARATUS FOR UNLOADING COMPRESSORS.

Application filed September 1, 1923. Serial No. 660,654.

This invention relates to air and gas compressors and pumps and to apparatus for unloading the same adapted to be controlled automatically in response to variations in receiver pressure. More particularly it concerns apparatus of this character in which valves are positively held open or closed by fluid pressure released in limited amount by a controller or actuator device responsive to predetermined receiver pressure.

Heretofore it has been customary to arrange the unloading valves to be operated by the fluid pressure released directly thereto by the actuator. Under favorable circumstances such operation is satisfactory even when a plurality of unloading valves are controlled by one actuator, as in large compressors. However in practice more or less leakage develops in the pipe lines due to the vibration of the machine and to other causes, resulting frequently in so reducing the pressure supplied to the unloading valves by the actuator that relative movement of the parts occurs as the compressor piston continues to reciprocate. Rapid wear follows with still greater leakage until complete failure of the unloading valves to operate results. It is not unusual also for irregular action of the unloading valves to arise from the presence of a particle of grit or of other foreign matter including water or oil, by reason of the restricted amount of fluid pressure admitted to the valves by the actuator.

Among the objects of the invention are to effect more reliable operation of the unloading valves, to provide means for this purpose simple in form, cheap to manufacture and easy to install upon either old or new compressors, and in general to overcome the defects of previous apparatus with a minimum of expense and trouble.

The invention comprises the interposition between the actuator device and the unloading valve or valves of an auxiliary valve directly controlled by the actuator and in turn adapted to subject the unloading valves to substantially full line or receiver pressure thereby to effect prompt and positive operation thereof in varying the load of the compressor.

In order to illustrate the invention one concrete embodiment thereof is shown in the accompanying drawings in which:

Figure 1 is a view partly in elevation and

partly in section, illustrating an installation of the invention; and

Fig. 2 is a sectional view on an enlarged scale of the invention, associated parts of the apparatus disclosed in Fig. 1 being indicated in dot and dash outline.

In the embodiment of the invention chosen for the purpose of illustration and illustrated in Fig. 1, actuators A and A', responsive to predetermined receiver pressure, control the operation of unloading valve assemblies B and B' upon the right and left ends respectively of the double acting compressor cylinder C, which is provided with a piston D reciprocated by any suitable source of power (not shown). Any number of actuators A and A' may be used to control the unloading valve assemblies B and B' to effect unloading of the compressor cylinder in any desired number of steps. While any desired and suitable type of actuator may be used, that illustrated in the drawings is disclosed and claimed in Patent No. 1,224,272 of May 1st, 1917, issued to myself and G. J. McFadden. Briefly this actuator or differential unloader A comprises a casing having a chamber a connected to the compressor receiver (not shown) by a pipe a' and having a second chamber a² normally open to atmosphere by ports a³. A valve a⁴ controls communication between chambers a and a² and normally closes chamber a through the action of a plunger a⁵ which maintains a yielding pressure upon the valve a⁴ due to the thrust of a spring a⁶, the tension of which may be varied by an adjusting screw a⁷ provided with a lock nut a⁸.

When the receiver pressure exceeds the pressure of spring a⁶, valve a⁴ is forced downwardly cutting off communication between chamber a² and atmosphere and admitting to chamber a² through restricted ports a⁹ pressure in limited amount to actuate the unloading valves. In practice it has been found necessary to make ports a⁹ few in number and very small in order that the air pressure against valve a⁴ may not be reduced to such an extent on unseating of the valve as to cause fluttering.

The unloading valves may, likewise be of any suitable or desired type and arranged to unload the compressor in any well-known manner as by holding open valves arranged to place the compressor chamber in communication with atmosphere or with clear-

ance pockets integral with the compressor cylinder or separate therefrom. The type of unloading valve disclosed in the drawing is that well-known in the art under 5 the name of "Simplite" valve and is shown and described in my prior Patent No. 1,275,843 issued August 13, 1918. In brief this valve comprises annular plates b normally maintained in contact with an aper- 10 tured valve seat b' by coil or volute springs b^2 mounted in a valve cage or keeper b^3 , these parts being secured to a stud b^4 held in place in a proper manner by the valve cover b^5 . The valve lifter b^6 is slidable on 15 valve stud b^4 being maintained in raised position by spring b^7 . To unload the compressor the valve lifter is forced against the valve plates b to hold the same spaced from seat b' by a piston b^8 movably by fluid pres- 20 sure admitted through a pipe b^9 .

In order to overcome failures and irregularities in operation of the unloading valves through insufficient pressure admitted by the restricted ports a^9 of the actuator valves, 25 which pressure is often still further diminished by leakage in the pipe connection or nullified by grit, oil and water carried to the movable parts by the motive fluid itself, auxiliary valves E and E', comprising the 30 present invention, are interposed between the actuator valves A and A' and the unloading valves B and B' controlled thereby for the purpose of subjecting the latter to full line or receiver pressure on operation 35 of the actuator valves as heretofore described. Each auxiliary valve comprises a casing 3 having an axial bore therethrough, enlarged at various points to form chambers. A piston 5, which may be hollowed out as 40 indicated to reduce its weight, is mounted for axial movement at one end of casing 3 in an enlargement 4 of the axial bore. The end of the casing 3 is closed in an air-tight manner by a suitable cover 6 having a pipe 45 7 communicating with chamber a^2 of the associated actuator valve whereby on admission of receiver pressure to chamber a^2 through restricted ports a^9 piston 5 will be moved downwardly in an obvious manner. 50 Piston 5 carries an axial extension or valve stem 8 extending through the bore of the casing 3, the lower end of which is subjected to the yielding pressure of a coil spring 9 bearing against a screw plug 10, 55 whereby the piston 5 is normally maintained in elevated position as shown in Fig. 1. The lower end of enlarged chamber 4 beneath the piston 5 forms a chamber 11 communicating with atmosphere through a passage 12. 60 Below chamber 11 and communicating therewith by an angularly disposed passage 13 is a second chamber 14 with which pipe b^9 of the unloader valve connects. Below chamber 14 is a third chamber 15 constantly 65 in communication with the compressor re-

ceiver by a pipe 16. Valve stem 8, of irregular size as shown, makes a tight fit with the axial bore of casing 3 immediately above chamber 14 and below chamber 15, intermediate which parts it is reduced in size 70 forming a neck 8'. Valve stem 8 has a beveled seat 17 below piston 5 adapted to cooperate with a seat 18 in chamber 11 and a second beveled seat 19 immediately below neck 8' adapted to cooperate with a seat 20 75 at the top of chamber 15; valves 17 and 19 being so positioned on stem 8 that they are alternatively in contact with their respective cooperating seats.

When the parts are in normal position, as disclosed in Fig. 1 with piston 5 near the top of its chamber, communication between chambers 15 and 14 is cut off, but established between chambers 14 and 11 by passage 13. Consequently the unloading valve is vented 80 to atmosphere and is in inoperative position for unloading the cylinder. When the receiver pressure builds up sufficiently to cause operation of the actuator valve or differential unloader the parts take the position 85 shown in Fig. 2, in which fluid pressure admitted to chamber 4 forces piston 5 downwardly seating valve 17, thus cutting off chamber 14 from atmosphere, and at the same time unseating valve 19 whereby the 90 full receiver pressure from pipe 16 passes through chamber 15 around reduced neck 8' to chamber 14 through pipe b^9 to piston b^6 of the unloading valve which in turn forces 95 valve lifter b^6 to hold valves b off their seats so long as the receiver pressure overcomes the spring a^6 of the actuator valve. When the receiver pressure is reduced and actuator valve a^4 again closes chamber a^2 , the pressure above piston 5 of the auxiliary 100 valve is vented through pipe 7, chamber a^2 and ports a^8 , whereupon valve stem 8 and piston 5 are forced upwardly by spring 9, thus closing valve 19 and opening valve 17, whereby the chamber of the unloading 105 piston b^8 is open to atmosphere through pipe b^9 , chamber 14, passage 13, chamber 11 and vent 12, thus rendering the unloading valve 110 inoperative.

From the above it will be apparent that 115 the auxiliary unloader valve forming the present invention is a separate and distinct unit adapted to work in conjunction with and auxiliary to regular or standard unloading mechanism, that its installation requires and involves no change whatever either in structure or in functioning of the original actuator or unloader or of the unloading valves, that while unloading mechanism can operate with or without the invention its 120 use as an auxiliary to such mechanism overcomes all irregularities and failures in the 125 operation of the unloading valves due to insufficient volume and pressure, that the device of the present invention is entirely auto- 130

matic in operation, and that in addition to ease of installation and positive operation it is characterized by such structural simplicity as to permit its production on a low cost basis.

Having described my invention what I claim as new is:

As a new article of manufacture, an auxiliary valve for use in compressor control systems and adapted to be inserted as a unit between the actuator or differential unloader valve and the unloading valves to act as a relay under control of said actuator for admitting the compressed fluid in volume and at full pressure to the unloading valves comprising a casing having a series of chambers in axial alignment, a piston in the upper chamber, a stem extending through the control chamber and cutting off communication axially between said control chamber and said upper chamber, a valve disposed in said lower chamber to control communication be-

tween the lower chamber and the control chamber, a single spring beneath said valve for normally maintaining the same in closed position and operating through said stem yeldingly to maintain said piston spaced from the lower end of said upper chamber, said upper chamber below said piston being vented to atmosphere, a restricted passage normally connecting said control chamber and the vented portion of said upper chamber, valve means on said stem adjacent said piston for closing said connection when said stem is moved by said piston to force said valve off its seat, and means for connecting the upper chamber above said piston to the actuator valve of the compressor control system, for connecting the control chamber to the unloading valves and for connecting the lower chamber to receive pressure.

Signed by me at Cleveland, Ohio, this 24th day of August, 1923.

WILLIAM H. CALLAN.
